ERNEST F. McGREGOR, OF NORWALK, CONNECTICUT.

WICK ADJUSTER.

Application filed December 9, 1925. Serial No. 74,306.

This invention relates to wick adjusters for a ship's light, such as a riding light or running light, or any light in which the font is placed in the frame from the bottom. In these ships' lights the law requires the use of a certain glass or globe such as Fresnel glass, and the use of this type of glass requires a construction which necessitates mounting of the font carrying the wick and the adjusting means therefor by inserting it upwardly through the bottom. There are other types of lights which do not use this particular type of glass which are also so constructed that the font is inserted through the bottom, and my wick adjusting means is equally adapted for this type of light. In these lights, in order to light the wick it is necessary to remove the font from the frame and adjust the wick outside before inserting it in the frame. The wick, therefore, must be set by guess because the conditions are different and the flame burns differently when the font is mounted in the frame or lantern than it does when outside. It also burns differently after the elements become warmed up than it does when the wick is first lighted and the elements are cold. It is, therefore, necessary for the user in lighting the lantern to place it in position for a while till it warms up and then adjust the flame to the proper height. In ships' lights this means that the light must be taken into the cabin or some place out of the wind, the font removed, the wick adjusted (again by guess) and the font replaced in the lantern. This obviously is the cut and try method and may mean several removals of the font before the proper adjustment has been reached. Furthermore, the vibration of an engine or dangling of the light in the wind is liable to jar the wick so that it is worked either up or down to reduce the flame or cause it to go out entirely. It is, therefore, an object of my invention to provide a simple device by which the wick may be adjusted while the font is mounted in the frame and without removing the font from the frame. It is also an object of the invention to provide an adjusting means which, after the wick has once been adjusted, will retain the wick in this position, so that the adjustment will not be changed by vibration, jarring, swinging in the wind and so forth; and it is a further object of the invention to pro-

vide a device of this character which may be quickly and easily attached to old lamps now in use as well as new lamps with practically no reconstruction of the lamp.

With the foregoing and other objects in view, I have devised a device, one form of which is illustrated in the accompanying drawing forming a part of this specification, similar reference characters being employed throughout the various figures to indicate corresponding elements. In this drawing,

Fig. 1 is a vertical section through the lower portion of a ship's riding light showing my improved wick adjusting device applied thereto.

Fig. 2 is a view of the font and its support with my adjusting device attached, looking from the right of Fig. 1.

Fig. 3 is a top plan view of the font and its support, the view being substantially on line 3—3 of Fig. 1.

Fig. 4 is a rear elevation of the adjusting device, and

Fig. 5 is an edge elevation thereof.

In the lamp shown the glass 10 is mounted in a metal frame or base member 11. This base or frame has an inwardly extending flange 12 at the bottom thereof provided with an opening 13 through which the font 14 is inserted and in which it is mounted. The font carries the usual wick 15, which is adjusted by a shaft 16 carrying a button 17 by which the shaft is rotated to adjust the wick up and down in the usual manner. The font is provided with a flange 18 forming a shoulder engaging the under side of the flange 12, and the font is secured in position by means of spring clamps 19. In the form shown these clamps are flat strips of metal bent to substantially the form shown in Fig. 2, the upper ends being secured to the outer surface of the font by any suitable means such as soldering, and intermediate their lengths they are bent inwardly on an incline as shown at 20. The lower free ends are preferably widened somewhat to form finger grips 21. When the font is inserted through the opening 13 in the base these springs will swing inwardly until the bend at the upper end of the incline 20 passes through the opening, when these clips will spring outwardly and this incline will rest on the top of the flange 12 and by camming action thereon will clamp the flange 18 on the font against the lower side of the flange 12, they,

therefore, clamp the font in position, but it may, however, be removed by merely pressing the free ends 21 toward each other to remove the inclines 20 from alignment with 5 the flange 12. It will be apparent that by pressing these free ends inwardly a short distance the spring clamps are relieved sufficiently to allow the font to be turned in the frame, and then when the spring clips are 10 released they will again clamp the font in the new position.

I have devised a simple and effective device which will utilize this turning movement of the font for adjusting the wick 15 either up or down without removing the font from the lantern. The form shown in the drawings comprises a finger member 22. This member in the form shown comprises a flat strip of metal bent upon itself at 20 a suitable distance from its upper end to provide two clamping portions 24 and 25. Below the portion 25 the finger is bent outwardly on an incline and then downwardly so that the free end portion 26 is offset from 25 the body portion 25 for a purpose presently to be described. The two substantially parallel portions 24 and 25 are spaced from each other a sufficient distance to allow for insertion of the button 17 between them, and 30 the rear portion 24 is provided with an elongated slot 27 extending upwardly from its lower end to receive the shaft 16 so that this shaft holds the finger from sliding laterally off the button. The portion 25 35 may also be provided with an elongated opening 28 to receive the projecting end 29 of the shaft, and the portions 24 and 25 are clamped on the opposite sides of the button by the thumb screw 30 extending through 40 the outer portion 25 and threaded into the inner portion 24. Thus the adjusting finger may be easily and quickly attached to the button and shaft and may be adjusted to any position desired about the shaft for 45 proper adjustment of the wick and then clamped in this adjusted position. The lower end 26 of this finger extends through a notch 31 in the flange 12 of the base or frame at one side of the opening 13. It will now 50 be apparent that if the font is turned in either direction the sides of the notch 31 will hold the lower free end of the finger stationary, and as the shaft is swung with the font as indicated by the arrows (a) in Fig. 2, the 55 finger will in effect be swung around the shaft as a pivot as indicated in Fig. 2, and as it is rigidly clamped to the shaft it will rotate the shaft as indicated by arrows (b) and adjust the wick up and down, depending in which direction the font is rotated. Thus the wick may be adjusted without removing the font from the lantern.

Another important effect is that as the font is clamped in different positions by the 60 spring clamps 19 the finger member 22 will

be held stationary by the walls of the notch 31, and therefore, it will hold the wick stationary and in any given adjusted position so that it cannot be jarred either up or down by vibration of the engine, swinging in the 70 wind and so forth.

With this device the font may be removed for cleaning, filling, adjusting and so forth practically as readily as it would without my attachment because the finger 22 will readily 75 pass from the notch 31, and it may be as readily reinserted in this notch. It will be noted that when in position in the lantern the flange 18 on the font will retain this finger in the notch so that there is no danger of its accidentally being shifted out of the notch and becoming inoperative. It will be obvious that this notch is merely a stationary holding means for the free end of the finger so that the same effect will be secured with any other holding means such as lugs or an eye or the like. It is also to be noted that as this adjusting device is a separate and independent element it may be attached to old lights now in use as readily 80 as to new lights, the only operation on or change in the old structure required being merely to cut the notch 31 in the flange of the base member. This may be readily done with a file or other suitable instrument. The 85 elongated slots 27 and 28 allow the adjusting finger to be mounted on buttons of different sizes so that the same finger may be used on all different buttons found in this type of lamp. It will be apparent that in 90 adjusting the wick all that is necessary is to drop the bottom cover 32 by releasing the spring catch 33, press inwardly a small amount on the spring clamps 19 and then turn the font either to the right or left the 95 required amount to adjust the wick, and it will be obvious this may be done while the font is mounted in its regular position in the lantern. After adjustment the spring clamps will clamp the font in its new position, and will also through the finger 22 hold the wick in its adjusting position.

Having thus set forth the nature of my invention, what I claim is:

1. In a lantern, a body, a font carrying a 115 wick mounted in said body and capable of a turning movement therein, a shaft for adjusting the wick, and a finger member connected to said shaft and held by engagement with the body so that a turning movement of the font will swing said finger and turn the shaft.

2. In a lantern, a body having an opening for insertion of a font and provided with a notch at one side of said opening, a font carrying a wick mounted in said opening and capable of a turning movement therein, rotatable adjusting means for the wick, and an operating member secured to said adjusting means and having a free portion 125

seated in said notch by which it is held so that a turning movement of the font will swing said member and adjust the wick.

3. In a lantern, a body, a font carrying a wick mounted in said body and capable of a turning movement therein, a rotatable shaft for adjusting the wick, an operating button on the shaft, an operating member detachably clamped to the button so as to be carried thereby, and means on the body to engage the free portion of said member to hold the same and turn the button by a turning movement of the font.

4. In a lantern, a body, a font carrying a wick mounted in said body and capable of a turning movement therein, means for normally holding said font against turning movement, means for adjusting the wick, and means connecting the adjusting means and the body member normally holding said adjusting means against movement and arranged to operate the adjusting means by a turning movement of the font.

5. In a lantern, a body, a font carrying a wick mounted in said body and capable of a turning movement therein, a rotatable shaft for adjusting the wick, an operating button on the shaft, an operating member comprising a flat strip bent upon itself to embrace said button and having a notch in one portion to receive said shaft, a screw to clamp

the opposed portions of the strip to the button, and means on the body to hold the said member to swing the same and adjust the wick by a turning movement of the font. 35

6. In a lantern a body having a flange provided with an opening for insertion of a font and provided with a notch at one side of said opening, a font mounted in said opening having a shoulder engaging the 40 under side of the flange, spring clamps on the font arranged to engage the upper side of the flange to clamp the font thereto, a wick carried by the font, a shaft for adjusting the wick, an operating finger secured to 45 the shaft and projecting through said notch and held in the notch by the font, said font being capable of turning movement to swing said finger and adjust the wick.

7. In an adjusting device for a lamp wick 50 mounted for adjustment by a rotatable shaft carrying an operating button, an operating member comprising a flat strip bent upon itself to embrace said button and having a notch in the free end of one side to receive 55 the shaft, means to clamp the member to the button, and the other portion of the strip being provided with an extension forming an operating finger to turn the shaft.

In testimony whereof I affix my signature.

ERNEST F. McGREGOR.
